UNITED STATES PATENT OFFICE.

ARTHUR BELL, OF RIDGEFIELD PARK, NEW JERSEY.

BOX-FINISHING MACHINE.

1,392,102.

Specification of Letters Patent. Patented Sept. 27, 1921.

Application filed April 13, 1921. Serial No. 461,056.

To all whom it may concern:

Be it known that I, ARTHUR BELL, a citizen of the United States, and a resident of Ridgefield Park, in the county of Bergen and State of New Jersey, have invented a new and Improved Box-Finishing Machine, of which the following is a full, clear, and exact description.

This invention has relation to box machinery and refers more particularly to a finishing machine for paper boxes which are provided with exterior coverings.

According to the present practice, after the outer sides of the box or lid has been covered, the operation of turning the edges of the covering within the mouth of the box and pressing the same thereto has been almost universally accomplished by hand principally due to the great variance in the sizes of the boxes and lids.

This invention contemplates and seeks for some of its principal objects to produce at a nominal cost an efficient finishing machine for this purpose by means of which the output and production will be materially increased with a minimum number of employees; a machine which will function to obtain a more perfect finish to the box than is now possible by hand labor; a machine in which means is provided to compensate for the great variance in the sizes of the boxes and lids, and a machine in which means of adjustment can be obtained whereby the same will properly handle boxes and lids made from material of different thicknesses.

With the above recited and other objects in view, the invention resides in the novel construction, combination and arrangement of parts set forth in the following specification, pointed out in the appended claims and illustrated in the accompanying drawings, it being understood that the right is reserved to embodiments other than those actually shown herein, to the full extent indicated by the general meaning of the terms in which the claims are expressed and by variations in the phraseology of the same.

In the drawings—

Figure 1 is a plan view of the machine illustrating the position of parts prior to the turning in and pressing operation.

Fig. 2 is a fragmentary front elevation illustrating the position of parts immediately after the turning in and pressing operation has been completed.

Fig. 3 is a side elevation illustrating the position of parts as shown in Fig. 1.

Fig. 4 is a longitudinal sectional view taken on the line 4—4 of Fig. 1 illustrating in full lines the position of parts as shown in Fig. 2 and in dotted lines the position of the parts as illustrated in Fig. 1.

Fig. 5 is a detail view illustrating the manner in which the adjustment of the clamping elements is accomplished.

Fig. 6 is an end view of the clamping finger guide.

Fig. 7 is a side elevation of one of the clamping fingers removed from the machine.

Fig. 8 is a detailed sectional view of one of the clamping plates illustrating the manner in which the same is associated with the supporting frame therefor.

Fig. 9 is a detailed horizontal sectional view taken approximately on the line 9—9 of Fig. 3.

Referring to the drawings by characters of reference which designate like parts throughout the several views thereof, the frame work of the machine includes a base 10 having vertical standards 11 at its forward end and rearwardly extending downwardly inclined side rails 12 supported at their forward end by the standards 11 and at their rear extremities by the brace bars 13. A backing plate 14 is mounted between the standards 11 at the upper end of the frame work and is adjustable forwardly or rearwardly by means of a stud bolt 15. A pair of supporting tables 16 and 17 are mounted directly in front of the backing plate 14 for independent vertical adjustments by means of the rack and pinion connection 18 and 19. The manipulating wheels 20 are keyed to the pinion shaft for the purpose of actuating the pinions to secure the adjustment of the tables. The backing plate is provided at its opposite ends with forwardly extending guide arms 21 disposed at a right angle thereto. By this arrangement boxes of various heights may be handled by the machine by adjusting the tables vertically to bring the upper edge of the box in a plane to register with the upper edge of the backing plate. The mechanism for turning in and pressing the edges of the box covering against the inner edges of the box mouth comprises a reciprocating U-shaped frame 22 which is mounted on the side rails 12 for sliding movement. The free extremities of the side arms of the frame 22 have

95

100

105

110

pivoted therebetween the free extremities of the side arms of a yoke 23. A channeled member 24 is adjustably mounted on the yoke by means of the threaded studs 25 which extend through the slots 26 in the body of the yoke and the clamping nuts 27 which are threaded thereon. The recess 28 in the channeled member 24 is adapted to respectively receive the lugs 29 provided on the clamping plates 30 and the guide blocks 31 for the clamping fingers. The clamping fingers 32 are respectively mounted between the guide ribs 33 of the guide blocks. A retaining bar 34 is arranged over the channeled member 24 and is secured at its opposite extremities to the side arms 23 of the yoke by means of the set screws 35 which are passed through the slotted extremities 36 thereof. The clamping fingers are provided with an enlarged head 37 at their upper end to provide a shoulder 38 at the junction of the head with the fingers which shoulders co-act with the retaining bar to limit the forward projection of the free end of the fingers with respect to the yoke. The head of each finger is provided with a stud 39 and the retaining member 34 is provided with a plurality of studs 40 corresponding in number with the number of clamping fingers and disposed in alignment with the studs 39. An elastic band or coiled contractile spring 41 is designed to operatively connect the studs 39 and 40 for normally effecting the movement of the fingers to engage the shoulder 38 with the retaining bar. The U-shaped frame is provided with a rearwardly projecting stem 42, the free extremity of which is maintained in contact with a cam 43 mounted on the cam shaft 44 by means of the springs 45 which are respectively secured at their opposite extremities to the frame 22 and the side rails 12. The swinging yoke 23 is connected by means of a link 46 to one extremity of the thrust rod 47 mounted in the bearing 48. The opposite extremity of the thrust rod is maintained in contact with the cam 49 by means of a spring 50. The cam 49 is mounted on a cam shaft 51 and said cam shaft is driven by the belt 52 and pulley connection 53 from a suitable motor 54. The cam shafts 51 and 44 are simultaneously driven in any suitable manner, a counter shaft 55 being shown for the purpose which is provided at its opposite ends with beveled gears 56 and 57. The beveled gears 56 and 57 respectively mesh with the bevel pinions 58 and 59 on the cam shafts 51 and 44.

In operation of the machine, the box A which has previously been covered by the covering B is set on one of the tables 16 or 17 with the open end arranged uppermost. The table 16 is adjusted vertically to bring the upper edge of the box A in registry 65 with the upper edge of the backing plate 14,

to dispose the projecting edges C of the covering B in the path of movement in the forward extremities of the clamping plates and fingers 30 and 32. As the sliding frame 22 is moved forwardly the forward extremities of the plates and fingers 30 and 32 will engage the edges C of the covering and bend the same over the upper edge of the box, the operator holding the box against the backing plate with one of the sides in contact with the guide arm 21. When the sliding frame 22 approaches the forward limit of its movement, the cam 49 will lift the thrust arm 47 to swing the yoke 23 to a vertical position thereby swinging the forward extremities of the fingers downward and within the mouth of the box A to turn the edge C of the covering B in over the upper edge of the side of the box and press and clamp the same thereagainst between the backing plate and the clamping plate and fingers. The clamping finger 32 which alines with one of the sides of the box will engage the same and be lifted thereby against the tension of the elastic band or spring. In order to positively insure the return of a lifted finger to its normal position, a yoke 60 is mounted on the yoke 23, the side arms 61 thereof being confined thereagainst by the retaining bar 34. The free extremities of the side arms 61 are provided with laterally extending projections 62 which co-act with the side arms of the frame 22 when the yoke 23 is swung to a vertical position whereby the cross bar or body of the yoke 60 is lifted out of contact with the heads of the clamping fingers to provide a clearance to permit the same to be lifted. When the frame 22 moves rearwardly and the yoke 23 is swung to a horizontal position the springs 63 will advance the cross bar of the yoke 60 into contact with all of the heads of the clamping fingers to return the same to normal position. The inclination of the side rails 12 of the frame 22 work of the machine causes the frame 22 to operate in an inclined plane whereby the forward extremities of the plates 30 and the fingers 32 will strike the free edge C of the covering B at an angle to minimize and practically eliminate the probability of tearing the same upon the initial turning over thereof. Inasmuch as the limit of the forward movement of the frame 22 is constant, it is necessary to adjust the backing plate 14 to compensate for boxes constructed from material of various thicknesses. Where the material from which the box is constructed is thin, the backing plate is adjusted to move its front face forward and wherever the stock is of thicker material it is adjusted rearward. In order that the extremities of the plates and fingers may exert a pressure throughout the full width of the turned-in portion of the covering, it may be 130

found necessary to adjust the channeled member 24 by sliding the same forwardly on the yoke 23 and this is accomplished by the loosening nut 27. Likewise the retaining bar 34 is adjustable forwardly to move the rear edge with which the shoulders abut in a forward direction. This is accomplished by loosening the set screws 35. The independent adjustability of the tables 16 10 and 17 permits one of the tables to be raised above the other to permit of the simultaneous use of the machine for finishing the box lids and boxes.

It will thus be seen that a simple and effective machine has been devised for turning in and pressing the edges of the box covering which is entirely automatic in its operation and which will operate in connection with boxes of various heights, widths 20 and lengths. It is obvious from the construction that where a large order of standard sizes of boxes are to be operated on, the fingers may be dispensed with and in lieu thereof plates may be employed entirely. 25 In this instance the width of one of the plates will represent the width of the interior of one dimension of the box while the width of a pair of combined plates will represent the length of the interior dimension 30 of the boxes.

I claim:

1. In a box finishing machine, a base plate against which the box sides are adapted to be successively held, means for registering 35 the edge of its mouth with the edge of the plate and means slidably over said registered edges and swingable downward within the mouth of the box, said means adapted to co-act with the extended portion of the box 40 covering to turn the same within the box mouth and press the same thereagainst to paste it thereto.

2. In a box finishing machine, a base plate against which the box sides are adapted to 45 be successively held, means for registering the edge of its mouth with the edge of the plate, means slidable over said registered edges and swingable downward within the mouth of the box, said means adapted to co- 50 act with the extended portion of the box covering to turn the same within the box mouth and press the same thereagainst to paste it thereto, and means for adjusting the sliding movement of said means over said 55 edges.

3. In a box finishing machine, a base plate against which the box sides are adapted to be successively held, means for registering 60 the edge of its mouth with the edge of the plate, means slidable over said registered edges and swingable downward within the mouth of the box, said means adapted to co-act with the extended portion of the box covering to turn the same within the box 65 mouth and press the same thereagainst to

paste it thereto, means for adjusting the sliding movement of said means over said edges, and means for adjusting said plate relative to the sliding means.

4. A machine of the character described 70 comprising an adjustable backing plate against which the box walls are adapted to be successively held, a member slidably and pivotally mounted with respect thereto, means carried thereby adapted to co-act with 75 the backing plate to effect the turning in of the surplus edges of the box covering and to exert a pressure thereon for sealing the same thereto.

5. In a machine for finishing covered 80 boxes, a backing plate against which the sides of the box are adapted to be successively held, means for registering the free edges of the box with one edge of the backing plate, a pivoted member mounted adjacent thereto and adapted to slide over said edge of the backing plate and means for swinging the forward edge of said member over the inner edge of the box side to turn the edge of the box covering into the mouth 85 of the box and press the same thereagainst for sealing it thereto.

6. A box finishing machine adapted to turn the edges of the covering and press the same against the inside of the box to seal it 90 thereto, including a backing plate, a reciprocating frame slidably mounted with respect thereto, clamping elements pivotally carried by said frame and adapted to be projected over one edge of the backing plate 100 and swung within the box to turn the edge of the covering thereover and press the same against the box edge between the backing plate and the clamping elements.

7. A box finishing machine adapted to 105 turn the edges of the covering and press the same against the inside of the box to seal it thereto, including a backing plate, a reciprocating frame slidably mounted with respect thereto, clamping elements pivotally carried by said frame and adapted to be projected over one edge of the backing plate 110 and swung within the box to turn the edge of the covering thereover and press the same against the box edge between the backing plate and the clamping elements, and mechanism for actuating the frame and said clamping elements.

8. In a machine for finishing boxes of the character described, a reciprocating frame, 120 a stationary backing plate located at the forward limit of movement of said frame, a pivoted yoke at the forward end of the first frame, a plurality of clamping elements carried by the pivoted frame and adapted to be projected beyond the forward edge of the backing plate, means for supporting a box with one side against the backing plate, means for registering the free edge of said side with an edge of the backing plate to 125 130

- dispose the extended portion of the covering in the path of movement of the clamping elements and mechanism for actuating the frames to project the forward extremities of the clamping elements over the box edge and swing the same into the box for turning the edge of the covering within the box and pressing the same thereagainst for sealing said edges together.
10. 9. A machine as characterized in claim 8, in which the clamping elements are mounted in the swinging frame for sliding movements whereby certain of said elements may be moved upward upon contact with the box

edges when the pivoted frame is swung to 15 dispose certain of the elements within the box.

10. A machine as characterized in claim 8, in which the clamping elements are mounted in the swinging frame for sliding movements whereby certain of said elements may be moved upward upon contact with the box edges when the pivoted frame is swung to 20 dispose certain of the elements within the box, and means for returning the said elements to normal position. 25

ARTHUR BELL.
